UNITED STATES PATENT OFFICE.

EDWIN O. KLEMM, OF DAYTON, OHIO, ASSIGNOR TO KLEMM MANUFACTURING COMPANY, OF SAGINAW, MICHIGAN.

CONTROL MEANS FOR GRAPHOPHONES.

1,417,747.

Specification of Letters Patent. Patented May 30, 1922.

Application filed December 6, 1919. Serial No. 343,106.

To all whom it may concern:

Be it known that I, EDWIN O. KLEMM, a citizen of the United States, residing at Dayton, in the county of Montgomery and State of Ohio, have invented certain new and useful Improvements in Control Means for Graphophones, of which the following is a specification.

The most common form of stopping and starting means used upon the sound producing machines today is the ordinary brake device manually controlled for the application of the brake and for the releasing thereof. In my pending application for patent, filed July 15, 1919, Serial Number 310,910, I propose the employment of brake means for controlling the movement of the record carrier or turn table, the controlling of which brake means is made a part of the function of the traveling tone arm which supports the reproducer, means being employed intermediate the tone arm and brake means so that the tone arm may be operated not only for rendering the stopping means active but for adjusting the same for inaction.

My present invention embodies improvements in the above mentioned construction of control means for the stopping and starting device of a graphophone.

In the first instance, I have improved upon the trip part carried by the tone arm or traveling part so that a positive interlocking of said trip with the brake detent may be obtained irrespective of the direction of movement imparted to the tone arm. By this feature I am enabled to obtain more easily and with possibly greater accuracy the proper adjustment of the trip necessary 40 preliminarily to predetermine the stoppage point in the reproduction of the record.

In addition to the foregoing, my invention resides in a general simplification of the construction of the brake controlling parts, and the provision of a number of alternative forms adapted for use under practical conditions of service and with different types of machines.

In the accompanying drawings—

50 Figure 1 is a view in side elevation and partly in section showing the base board of a graphophone of a well known type, the

motor frame and the parts forming the invention provided intermediate the tone arm and governor shaft.

55 Figure 2 is a fragmentary sectional view taken about on the line 2—2 of Figure 1.

Figure 3 is a perspective view of the brake lever and its supporting and attaching parts.

60 Figures 4 and 5 are sectional views taken about at right angles to each other illustrating a modification of the improvements.

Figure 6 is a fragmentary sectional view of a further modification.

65 Figure 7 is a fragmentary sectional view of the modification shown in Figure 6 showing how the brake is applied to the turn table externally of the same.

70 The parts of my invention are so simple in their construction and arrangement that they will be readily understood upon reference to the following description in connection with the drawings embodying the figures above outlined. In these drawings the 75 base of the graphophone is designated A and the record carrier or turn-table B. C is the record on the turn-table. D the spindle with which the carrier B rotates when the machine is in operation, and E is the motor 80 frame which is of any conventional type. There is utilized in connection with the motor of the machine, not illustrated, the governor shaft 1 and its customary disk 2. The stopping and starting of the motor is effected according to the construction in Figures 1 to 3 inclusive by a brake lever 3 pivotally supported at 4 upon a depending bracket 5 attached to the motor frame by a suitable fastening 6. The lever 3 is 85 equipped with a suitable brake shoe 7. A spring 8 normally tends to hold the lever 3 with the brake or shoe 7 applied to the disk 2, this being the stopping position.

90 The means of my invention in addition to the advantageous attachable form of the brake parts just described includes a detent 9 vertically movable on the base A and preferably passing through an opening 10 in said base. The detent 9 is in the simple 100 form of a vertically movable plate and is supported in a tubular guide or member 11 attached to the base A. At its lower end, the detent 9 is forked at 12 to receive and en-

gage the free end of the brake lever 3 for operative connection with the latter. Outstanding from the upper end of the detent 9 and preferably integral therewith is an 5 arm 13 and practically at the upper extremity of the detent 9 is a vertical projection or stop 14 and a notch 15.

Mounted upon the traveling part or tone arm F, I provide an adjustable trip 16 consisting primarily of a ring like portion frictionally engaging and encircling the tone arm adjacent to the point of support of the latter on the base A, and an offstanding arm disposed so as to extend over the detent 9 10 and its arm 13. Furthermore, the trip 16 is disposed so that it may be received by the notch 15 of the detent 9 when the parts 15 and 16 are opposite one another at which 15 time the spring 8 will raise the lever 3 and the detent 9 and cause the parts 15 and 16 20 to interlock.

With an understanding of the construction as above presented, it will be obvious that while the parts 9 and 16 are interlocked, 25 as shown in Figures 1 and 2, the operator may slightly elevate the tone arm F and by movement of the same in either direction, the relation of the parts 9 and 16 remaining fixed during such movement, the reproducer 30 stylus may be carried to any point in the length of the record, usually its inner terminal, in order to set the mechanism for stopping automatically at such place. Thereafter the operator will raise the tone arm 35 or traveling part F sufficiently to carry the trip 16 out of the notch 15, then swing the arm F toward the point of the record at which it is desired to start reproduction, usually the beginning of the record. In this swinging movement, the arm F may be 40 caused to engage the upper edge of the arm 13 to depress the detent 9 sufficiently to cause release of the brake through downward movement of the lever 3. The deposit of 45 the stylus of the reproducer 17 upon the record makes necessary downward pressure of the trip 16 on the arm 13 sufficient to maintain the brake lever 3 and its brake shoe 7 in released positions until the trip 16 travels 50 over the arm 13 back to a point opposite the notch 15. At this time the spring 8 will lift the detent 9 and shoe 7 for application of the brake to the governor disk 2 and stoppage of the machine. On account of the 55 frictional action between the parts F and 16 variation in adjustment of the trip 16 is obtainable so that irrespective of the size of the record the manipulation of the trip by the arm F may be obtained under any 60 conditions so as to predetermine the point of stoppage of reproduction in the length of the reproducing zone on the record C. The sole requirement of the operation of my invention is that the tone arm F be manipulated 65 to predetermine the stopping point of

reproduction and then shifted to the starting point and deposited so that the stylus is upon the record, the latter action insuring the automatic starting of the machine if that has not already been performed by the 70 downward pressure of the part 16 on the arm 13. The above operation is practically about all that is required of the operator at the present time in the use of the ordinary graphophone as regards the movement of 75 the tone arm alone.

It is, of course, clear that the parts 9 and 11 may be of any suitable form in cross section such as round, square, or otherwise than 80 oblong as illustrated.

The modification of Figures 4 and 5 is of self evident construction working practically on the identical principle above disclosed excepting that the detent 9' is pivoted instead of sliding and mounted upon a pivotal support or bracket 11'. The parts 3', 11', 13', 15', 14' and 12' are equivalent in function to the parts 3, 11, 13, 15, 14 and 12 previously set forth. The brake lever 3', as seen in Figure 5, is pivoted intermediate its 90 ends, however. The parts otherwise are practically as above set forth in respect to Figures 1 to 3 inclusive and have the same reference characters.

As per Figures 6 and 7 the construction 95 proposed by me is practically the same as disclosed at the out start hereof excepting that the brake lever 3'' has its brake shoe 7'' arranged to engage the turn table B instead of the governor disk as shown in Figures 1 to 5 inclusive. I have designated the parts in Figures 6 and 7, equivalent to the parts 3, 8, 9, 13, 14, 15, 16, 11 and 12, as 3'', 8'', 9'', 13'', 14'', 15'', 16'', 11'' and 12'' respectively.

Having thus described my invention what I claim as new is:—

1. In graphophone mechanism, the combination with a record carrier, a reproducer arm having a reproducer to traverse a record upon said carrier, of a stopping device for the carrier, a trip on the arm, and a controlling detent connected with the stopping device, the last two parts being adapted to interlock for adjusting the trip relatively to 110 the arm to predetermine the time when the stopping means shall become effective, and to cooperate to move the detent for retracting the stopping means to permit starting of the carrier for reproduction.

2. Means as claimed in claim 1 in which the trip is arranged to press and retract the stopping device to permit operation of the carrier when the reproducer arm is in a position for the reproduction of the record.

3. In graphophone mechanism, in combination, a record carrier and the traveling reproducer arm associated therewith, together with a trip adjustable on the arm, brake means for stopping the carrier, and 130

- detent means intermediate the trip and
brake means for cooperation with the trip
for retracting the brake means and adapted
to interlock with the trip to hold the latter
5 relatively stationary during movement of
the reproducer arm under certain condi-
tions, the said trip being movable with the
reproducer arm under other conditions of
relative adjustment of the trip and detent.
- 10 4. In graphophone mechanism, in com-
bination, a record carrier and the traveling
reproducer arm associated therewith, to-
gether with a trip adjustable on the arm,
brake means for stopping the carrier, and
15 detent means intermediate the trip and brake
means for cooperation with the trip for
holding the brake means retracted during
operation of the carrier for reproduction
and adapted to interlock with the trip to
20 hold the latter relatively stationary during
movement of the reproducer arm under cer-
tain conditions, the said trip being movable
with the reproducer arm under other condi-
tions of relative adjustment of the trip and
25 detent to release the trip from its interlock-
ing engagement with said detent.
5. In graphophone mechanism, in com-
bination, a record carrier and the traveling
reproducer arm associated therewith, to-
30 gether with a trip adjustable on the arm,
brake means for stopping the carrier, and
detent means intermediate the trip and
brake means for cooperation with the trip
for retracting the brake means and holding
35 the latter retracted during operation of the
carrier for reproduction and adapted to in-
terlock with the trip to hold the latter rela-
tively stationary during movement of the re-
producer arm under certain conditions, the
40 said trip being movable with the reproducer
arm under other conditions of relatively ad-
justment of the trip and detent to release the
trip from its interlocking engagement with
said detent.
- 45 6. In graphophone mechanism, in com-
bination a record carrier and the traveling
reproducer arm associated therewith, to-
gether with a trip adjustable on the arm,
brake means for stopping the carrier, and
50 detent means intermediate the trip and
brake means for cooperation with the trip
for retracting the brake means and adapted
to interlock with the trip to hold the latter
relatively stationary during movement of
55 the reproducer arm under certain conditions,
the said trip being movable with the repro-
ducer arm under other conditions of relative
adjustment of the trip and detent, the said
detent being equipped with a member
60 against which the trip bears during the re-
producing operation of the reproducer arm
so as to maintain the detent in a position
holding the brake means inactive.
7. In graphophone mechanism, in com-
65 bination a record carrier and the traveling
reproducer arm associated therewith, to-
gether with a trip adjustable on the arm,
brake means for stopping the carrier, and
detent means intermediate the trip and brake
70 means for cooperation with the trip for re-
tracting the brake means and adapted to in-
terlock with the trip to hold the latter rela-
tively stationary during movement of the
reproducer arm under certain conditions, the
75 said trip being movable with the reproducer
arm under other conditions of relative ad-
justment of the trip and detent, the said de-
tent being equipped with a member against
which the trip bears during the reproducing
80 operation of the reproducer arm so as to
maintain the detent in a position holding the
brake means inactive, the portion of the de-
tent adapted to interlock with the trip being
arranged so that the parts will automatically
85 interlock when the reproducer arm reaches
a predetermined point in its movement.
8. In combination, graphophone mech-
anism including a record carrier and travel-
ing reproducer arm, brake means for the
carrier, a detent to retract the brake means
90 comprising a member slidable parallel with
the axis of movement of the reproducer arm,
and an adjustable trip on the reproducer
arm to actuate the detent to retract the brake
means. 95
9. In combination, graphophone mech-
anism including a record carrier and travel-
ing reproducer arm, brake means for the car-
rier, actuating means for the brake means
tending to constantly apply the latter, a de-
100 tent to retract the brake means comprising
a member slidable parallel with the axis of
movement of the reproducer arm, and an
adjustable trip on the reproducer arm to
actuate the detent to retract the brake means. 105
10. In combination, graphophone mech-
anism including a record carrier and travel-
ing reproducer arm, brake means for the
carrier, a detent to actuate the brake means
comprising a member slidable parallel with
110 the axis of movement of the reproducer arm,
and an adjustable trip on the reproducer arm
arranged to operatively engage said member.
11. In combination, graphophone mech-
anism including a record carrier and travel-
ing reproducer arm, brake means for the
carrier, a detent to actuate the brake means
comprising an elongated member arranged
115 for longitudinal movement only and in a
direction parallel with the axis of movement
of the reproducer arm, and an adjustable trip
on the reproducer arm to actuate said mem-
ber.
12. In combination, graphophone mech-
anism including a record carrier and travel-
ing reproducer arm, brake means for the car-
rier, a trip on the reproducer arm adjusta-
ble thereon to predetermine the time when
the brake means shall become effective, and
a detent to actuate the brake means compris- 130

ing a vertically sliding member disposed adjacent to the reproducer arm and having an offstanding arm against which the trip is adapted to bear to hold the brake means retracted during reproducing action of the reproducer arm.

13. In combination, graphophone mechanism including a record carrier and traveling reproducer arm, brake means for the carrier, a trip on the reproducer arm adjustable thereon to predetermine the time when the brake means shall become effective, and a detent to actuate the brake means disconnected therefrom comprising a vertically 10 sliding member disposed adjacent to the reproducer arm and having an offstanding arm against which the trip is adapted to bear to

hold the brake means retracted during reproducing action of the reproducer arm.

14. In combination graphophone mechanism including a record carrier and traveling reproducing arm, brake means for the carrier, an adjustable trip on the reproducing arm, and a detent to actuate the brake means comprising a slideable member having 20 a portion disposed so as to interlock with the trip to hold the latter stationary during certain movement of the reproducing arm, and another portion adapted to be engaged by the trip so as to maintain the detent in a 25 position holding the brake means inoperative.

In testimony whereof I affix my signature.
EDWIN O. KLEMM.
